CASTING APPARATUS

Albert H. Jung, Flushing, N. Y., assignor to United American Metals Corporation, Brooklyn, N. Y., a corporation of New York

Application April 29, 1939, Serial No. 270,808

5 Claims. (Cl. 22—79)

This invention relates to casting and more particularly to the delivery of molten metal from a furnace into a multiple mold.

Prior to the instant invention it has been customary to associate a metal pouring spout or chute in either fixed or pivotal relation to a discharge opening in a metal melting furnace in order that the outer end of the chute may be lowered when the mold is in place and ready to be filled, and the discharge end raised above the discharge opening when the mold is full and it is desired that the flow of molten metal be discontinued. While such prior constructions effect flow and discontinuance of flow of molten metal when desired, yet the continuous use of such devices has been wasteful of metal by reason of excessive formation of dross which occurs while the chute is being raised and lowered with the surface of molten metal therein exposed to the air.

It is an object of the instant invention to provide a swingable molten metal chute in association with the discharge of a furnace capable of being swung in the same horizontal plane, whereby the formation of dross is minimized.

It is a further object of the instant invention to provide a swingable metal chute in association with a molten metal furnace incorporating combined means for controlling the swinging of the chute and the flow of molten metal therethrough, whereby the filling of a plurality of molds may be effected by the control of the device with but a single hand of the operator.

Other objects and the nature and advantages of the invention will be apparent from the following description taken in conjunction with the accompanying drawing, wherein:

Fig. 1 is a view in perspective illustrating a swingable pouring spout in accordance with the invention;

Fig. 2 is a sectional view taken along line 2—2 of Fig. 1 and looking in the direction of the arrows; and,

Fig. 3 is a fragmentary longitudinal sectional view illustrating a modified form of gate.

Referring to the drawing a metal melting furnace 10 is provided with a discharge opening 11. Immediately below the furnace discharge opening 11 and in pivotal relation with the furnace 10 is a swingable chute 12 arranged to be swung in a generally horizontal plane whereby the individual molds 13 may be successively filled from the lowermost discharge end 14 of the molten metal chute 12. The pivot joint 15 is secured to the outer wall of the furnace 10 and the under side of the molten metal chute 12, but any other arrangement or connection associated with the chute 12 or the furnace 10 or both may be substituted for the construction illustrated in order to effect the generally horizontal swing-

ing of the metal chute 12 about the inner end thereof which is adjacent to the discharge opening 11 in the furnace 10.

The furnace 10 forms no part of the instant invention and may generally comprise a melting pot and heating means of any type such as a gas burner, a coal burner, or electrical resistance element. The metal discharged flows through the opening 11 and passes into the enlarged inner end of the chute 12 which is of generally U-shaped section, from whence it flows to the relatively small discharge end 14 and into the individual mold cavity 13 of the multiple mold 16. Arranged in association with the walls of the chute 12 and located closer to the discharge end 14 than to the receiving end thereof is a pivotably mounted gate 17 comprising a generally flat element shaped along the bottom and side edges to correspond to the U-shaped section of the cavity of the chute 12. A U-shaped frame member 18 engages the outer wall of the chute 12 and is secured thereto by bolts 19. The arms 20 of the U-shaped frame member 18 extend above the sides of the chute 12 to form a support for the gate 17. The pivot pins 21 secure the gate 17 in pivotal relation to the arms 20 of the frame member 18 whereby the gate 17 may be swung into open and closed position to effect flow of molten metal or discontinue such flow. In order to provide a neat fit between the lower portion of the gate 17 and the inner walls of the chute 12 a band 22 may be associated with the lower portion of the gate 17 which may be ground to give the required contour corresponding to the cavity of the chute 12.

With the furnace 10 in operation and the multiple mold 16 arranged beneath the open discharge end 14 of the swingable chute 12, the operator may move the chute 12 by corresponding movement of the handle 23 which is secured to the side wall of the chute 12 by the angularly bent rod 24, until the discharge end 14 is immediately above an individual mold cavity 13 of the mold 16 and the filling of the individual mold cavity 13 will be effected without further attention of the operator. When the individual mold cavity 13 is full, the operator pulls the trigger element 25 which is associated with the upper portion of the gate 17 by the chain 26 to effect closing of the gate 17 which is normally held open by the tension springs 27 also secured to the upper end of the gate 17 at the side of the same. The other end of the tension springs 27 are secured to the lower ends of inverted J-shaped spring holders 28 which are secured at their upper ends in mating engagement with the side walls of the chute 12. One of the individual mold cavities 13 being full and the gate 17 being closed, the operator then moves the handle 23 to effect corresponding

movement of the chute 12 until the discharge end 14 of the gate 17 is directly above a successive mold cavity 13 which is ready to be filled. The operator then releases the trigger 25 and 5 the tension spring 27 effects the partial rotation of the gate 17 about the pivot pins 21 to open the chute 12 which passes molten metal from the furnace 10 through the discharge opening 11 into the chute 12 to its discharge end 14 from 10 whence the second mold cavity receives metal until the operator again pulls the trigger 25 to again close the chute 12 to further flow. This process is repeated until all of the individual cavities in the multiple mold are filled, whereupon a second multiple mold 16 may be placed 15 in position beneath the swingable chute 12. Not only is it contemplated that multiple molds 16 be utilized in connection with the swingable chute 12 but it is to be understood that it is 20 within the scope of the invention to utilize the device in association with molds arranged on a continuous conveyer.

With the construction above described no vertical swinging of the chute is contemplated for 25 the control of flow of molten metal is affected by the gate 17 whereby the exposed surface of the molten metal flowing in the chute 12 will have a minimum of formation of dross thereon and further the operator will be called upon to expend 30 but little energy in the filling of many molds.

The formation of dross due to oxidation of the metal on its surface is encouraged by motion of the metal through vertical space and this formation is quite an item of expense in the handling 35 of molten metal and savings due to the elimination of the formation thereof are appreciable. Devices in accordance with the instant invention not only inhibit the formation of dross by an arrangement which effects satisfactory control thereof without vertical movement, but they 40 may be operated with the expenditure of minimum energy on the part of the operator whereby a single operator may stay at his post a longer time without tiring.

45 It will be obvious to those skilled in the art that various changes may be made in this device without departing from the spirit of the invention and therefore the invention is not limited to what is shown in the drawing and described in the specification but only as indicated 50 in the appended claims.

What is claimed is:

1. A molten metal distribution chute of generally U-shaped section larger at its molten metal 55 receiving end and smaller at its molten metal discharge end, a pivotal connection directly connected to said chute at its metal receiving end, said pivotal connection having a vertical axis whereby the discharge end may be swung in a 60 generally horizontal plane thereabout, the molten metal receiving end of said chute located adjacent to the discharge end of a molten metal source, means for generally horizontally swinging the discharge end of said chute to successive 65 positions adjacent a series of individual molds cavities, a gate pivotably mounted within said chute and engaging the inner walls thereof in its closed position to effect flow of molten metal therethrough, spring means normally under tension connected to the upper portion of said gate, 70 acting to hold said gate in its open position whereby the flow of molten metal through said chute is permitted, a generally U-shaped frame

member corresponding to the exterior of the chute but having side legs longer than the height of the walls of the chute to provide for the said pivotal arrangement of the gate, pivot pins engaging said side legs and said gate in pivotal relation, trigger operated means engaging said gate at a location above the plane of said pivot pins and said means for swingably moving said chute, said trigger operating means comprising a trigger located adjacent to said means 10 for swingably moving said chute, whereby an operator may move said chute and control said gate with a single hand and whereby the operator may effect control of the flow of molten metal from said source and fill successive mold 15 cavities without vertical movement of said chute.

2. The structure recited in claim 1, and inverted J-shaped means secured to the upper ends of the side walls of said chute and its opposite ends to the spring means which is associated 20 with the said gate.

3. The combination of a furnace, means forming a molten metal discharge opening, a distribution chute open at its top adjacent and below said discharge opening means at one end of said chute, said distribution chute being substantially vertically pivoted for substantially horizontal movement about that end which is associated with said furnace, a gate mounted in said chute, means for operating said gate, means connected 30 to said chute for effecting movement thereof in a substantially horizontal plane, said gate operating means and said chute moving means being located within a handspan of each other whereby both said gate and said moving means may be 35 operated with a single hand.

4. The combination of a furnace, means forming a molten metal discharge opening, a distribution chute open at its top adjacent and below said discharge opening means at one end of said chute, said distribution chute being substantially vertically pivoted for substantially horizontal movement about that end which is associated with said furnace, a gate mounted in said chute, means for operating said gate, means connected 40 to said chute for effecting movement thereof in a substantially horizontal plane, said gate operating means and said chute moving means being located within a handspan of each other. 45

5. The combination of a furnace, means forming a molten metal discharge opening, a distribution chute open at its top adjacent and below said discharge opening means at one end of said chute, said distribution chute being substantially vertically pivoted for substantially horizontal movement about that end which is associated with said furnace, a gate mounted in said chute, means for operating said gate, means connected 55 to said chute for effecting movement thereof in a substantially horizontal plane, spring means normally urging said gate to its open position, said gate operating means including an element actuatable to overcome the action of said spring and effect the closing of said gate, said gate 60 operating means and said chute moving means being located within a handspan of each other. 65
